UNITED STATES PATENT OFFICE.

GILBERT BREWSTER, OF HARVEY, NEW BRUNSWICK, CANADA, ASSIGNOR
OF ONE-HALF TO T. A. BLACKADAR, OF SAME PLACE.

HOLLOW-WARE CLEANER.

SPECIFICATION forming part of Letters Patent No. 242,745, dated June 14, 1881.

Application filed February 7, 1881. (No model.)

To all whom it may concern:

Be it known that I, GILBERT BREWSTER, of Harvey, in the county of Albert, Province of New Brunswick, and Dominion of Canada, have invented certain new and useful Improvements in Apparatus for Cleansing Hollow Wares, of which the following is a specification.

My improvements relate to contrivances for cleaning the inside of bottles, lamp-chimneys, and other hollow wares, where the difficulty is in reaching the surface to be cleaned with a cloth or brush or other substance by which rubbing may be produced; and the nature of my invention will be apparent from the following description, taken in connection with the drawings, in which—

Figure 1 shows, in section, a form of apparatus embodying my improvements, and Fig. 2 shows a cross-section of the stock A through the stop S.

A is a stock or staff, which may be of wood or metal, small in diameter and round.

B is an air-tight flexible sack, which, as I prefer to make it, is of a thin rubber body, covered with crash or some napped or rough material, and which is made tight to the stock A at x and y, either by stretching on or winding with thread or wire, or cementing.

D is crank by which the contrivance is made to revolve.

c is the nap or rough surface on B.

d d' is a hole or air-conduit leading from near one end outside to the inside of B.

S is a stop or valve, intended to open and close the air-conduit d d', and which may be either an open-and-shut slide or a plug-cock, or, as I prefer to make it, and as shown in the

drawings, a slightly-tapering cylinder, p, sliding in the stock A and having a cap, e f, at either end, a perforation, q, to correspond with the hole d, and a coiled spring, s.

The operation of this contrivance is as follows: The stop S being opened to let out the air, the bag B is compressed, and the apparatus may be easily thrust, the end a first, into the neck of a bottle or into a lamp-chimney, for instance; then, with the thumb compressing the knob or cap e, the operator brings the holes q and d opposite, inflates B with the breath, and lets go e, and the action of the spring s closes the stop S, and the air within B holds it against the sides of the hollow-ware in every part. Then, by holding the ware with one hand and turning the crank D with the other, the outer surface c of the bag B is made to revolve and operate in connection with soap-suds or other cleansing liquid.

This contrivance may be easily modified in size or proportions or arrangement of the parts to suit any size or style of hollow-ware. It is cheaply made, and affords a perfect conformity of the rubbing or operative surface to the interior sides of the ware.

I claim as new and of my invention—

1. A cleansing apparatus consisting of a stock A, an air-duct, d d', and a compressible and inflatable bag, B, constructed substantially as and for the purposes described.

2. The combination of stock A, bag B, air-duct d d'; and stop S, substantially as shown and set forth.

GILBERT BREWSTER.
